UNITED STATES PATENT OFFICE.

ANDREW McTERNEN, OF ANDOVER, MASSACHUSETTS.

DESIGN FOR A SAFETY-BAND FOR POCKET-BOOKS.

SPECIFICATION forming part of Design No. 24,542, dated August 13, 1895.

Application filed June 27, 1895. Serial No. 554,270. Term of patent 14 years.

To all whom it may concern:

Be it known that I, ANDREW McTERNEN, a citizen of the United States, residing at Andover, in the county of Essex and State of Massachusetts, have invented and produced a new and original Design for Safety-Bands, of which the following is a specification.

This invention relates to a new and original design for safety-bands for pocket-books, &c.; and it consists in the novel shape and configuration hereinafter fully described, illustrated, and claimed, reference being had to the accompanying drawing, showing a part thereof.

5 The drawing illustrates a perspective view of my design.

The leading feature of my design consists in a band provided upon its exterior side with triangular-shaped projections.

a represents a band, which is continuous, 20 forming a ring, as shown. Upon the exterior of this band or ring are formed triangular-shaped projections *a'*, arranged in a symmetrical manner about the ring or band.

What I claim is—

25 The design for a safety-band, substantially as shown and described.

In testimony whereof I have signed my name to this specification, in the presence of two subscribing witnesses, this 22d day of 30 June, A. D. 1895.

ANDREW McTERNEN.

Witnesses:

H. L. ROBBINS,
A. D. HARRISON.
